UNITED STATES PATENT OFFICE

113,194

DESIGN FOR A COMBINED COAT AND HEAD COVERING

Emma A. Storey and Daniel E. Vertuno,
Oak Park, Ill.

Application August 20, 1938, Serial No. 79,468

Term of patent 3½ years

To all whom it may concern:

Be it known that we, Emma A. Storey and Daniel E. Vertuno, citizens of the United States, residing at Oak Park, in the county of Cook and State of Illinois, have invented a new, original, and ornamental Design for Combined Coat and Head Covering, of which the following is a specification, reference being had to the accompanying drawing, forming part hereof.

In the drawing,—

Fig. 1 is a front elevational view of a combined coat and head covering embodying my new design;

Fig. 2 is a side elevational view thereof; and
Fig. 3 is a rear elevational view thereof.

We claim:—

The ornamental design for a combined coat and head covering, substantially as shown.

EMMA A. STOREY.
DANIEL E. VERTUNO.
